UNITED STATES PATENT OFFICE.

ROBERT T. MORRIS, OF NEW YORK, N. Y.

MELTING APPARATUS.

1,379,200.

Specification of Letters Patent. Patented May 24, 1921.

Application filed November 19, 1919. Serial No. 339,239.

To all whom it may concern:

Be it known that I, ROBERT T. MORRIS, a citizen of the United States, and a resident of the city of New York, borough of Manhattan, county and State of New York, have invented an Improvement in Melting Apparatus, of which the following is a specification.

This invention relates to apparatus for melting various substances.

One of the objects of this invention is to provide a simple and practical melting apparatus of durable and rugged construction. A further object is to provide an efficient melting apparatus in which the heat is most effectively used and with a minimum loss and in which any desired degree of fluidity of the melted substance may be maintained in a simple manner, with the minimum number of adjustments and with the minimum consumption of heat and therefore of fuel. This invention aims also to provide a melting apparatus which will function in the above manner irrespective of surrounding temperatures and with a minimum interference from the effects of violent atmospheric or other air currents. Still a further object is to provide a melting appliance of the above type which will be readily portable and in which the above features are so embodied that simplicity of construction and efficiency of operation are maintained. Other objects will be in part obvious and in part pointed out hereinafter.

The invention accordingly consists in the features of construction, combinations of elements, and arrangements of parts which will be exemplified in the construction hereinafter described and the scope of the application of which will be indicated in the appended claim.

The single figure in the drawing is a side elevation showing by way of example one of the varied possible embodiments of this invention.

This invention relates more particularly to the art of grafting and aims to provide an apparatus for melting wax of the type used in the grafting of trees, shrubbery, and the like. The illustrative form shown here-with is especially adaptable for such use but it is to be understood that various other embodiments and uses may be made of this invention without departing from the scope and spirit thereof.

Referring to the figure in the drawing

there is shown a melting apparatus comprising a main frame built up preferably of heavy steel vertically-extending wire members 10 and a horizontally extending circular member 11 to which the vertical steel wires 10 are connected by means of the metal cleats 12. The vertical members 10 are conformed to produce a reduced section and at such section are suitably fastened to 60 a heavy metal ring member 13 for a purpose to be hereinafter described. At their lower extremities the vertical members 10 extend in an outward direction and at their extreme ends are fastened by bending to a 65 heavy circular member 14 forming a base of sufficient lateral expance to give the entire structure great stability. The members 10 at their upper extremities terminate in a circular ring member 15 shown in dotted 70 lines to which they are fastened in a suitable manner such as by riveting or welding.

A metallic canopy 16 of the general shape as illustrated is mounted directly upon the ring member 15 and is fastened thereto by 80 a hinge structure 17 shown in dotted lines and held in its normal position as shown by means of the coöoperating latch members 18 and 19. Fastened at points diametrically 85 opposite and on the under-side of the ring member 15 and extending upwardly are two wire links 20 to which are connected the hook-shaped ends 21 of a wire bail 22. The two vertical members 10 immediately below the diametrically opposite points at which the hook members 20 are fastened to the ring member 15 are shaped in the form of a 90 ring member 23 extending in a plane perpendicular to the plane of the drawing and extending in line with the vertical or 95 straight portions of the wire bail 22. The right-hand ring member 23 extends in a forward direction and the left-hand member 23 extends in the reverse or rearward direction and serves the purpose of preventing the bail 22 from dropping entirely to the lower sides of the main frame. Thus, should the bail 22 fall forward its fall will 100 be arrested as soon as the straight portion thereof contacts with the right-hand member 23 to maintain the bail 22 in a substantially horizontal plane. Maintaining the bail in such a plane at all times holds the circular bail portion well protruding from the sides of the main frame so that the bail 110 may be readily clasped by the hand. The same action takes place should the bail fall

to the rear, though in such case the left-hand ring member 23 functions as hereinbefore described.

Mounted within and securely fastened to the ring member 13 at the reduced portion of the main frame is a metallic base member 24 having in general a cup shape and provided with a reduced portion 25 into which is fitted a container 26. In the upper end of the container 26 is mounted a wick holder 27 provided with a wick 28 and a handle 29 for adjusting the height of the wick 28 within the wick holder 27. The base member 24 is provided with a series of perforations 30 extending around its circumference for purposes to be hereinafter mentioned. Extending from the upper portion of the base member 24 to the reduced portion of the canopy 16 is a chamber 31 of a general cylindrical construction and having its lower and upper ends so shaped as to substantially fit into the base member 24 and the reduced portion of the canopy 16 respectively. The reduced portion of the canopy 16 is provided with a series of perforations 38 extending circumferentially around the upper portion of the canopy, the purposes of which will be hereinafter described.

The upper part of the canopy 16 is provided with an annular sheet metal top member 32 which serves to receive and support the receptacle 33. The receptacle 33 is in general of a cylindrical form having preferably a slight taper in the direction of its bottom and has formed at its upper edges a lip 34 which may coöperate with the top member 32 to support the container 33. The receptacle 33 is provided at preferably one point in its upper edge with a spout 35 and with a wire bail member 36 bent into the shape shown and extending through two holes in the upper edge and under the lip 34 of the receptacle 33. The top member 32 is provided with a small cut-away portion 37 into which the spout 35 is accommodated and which serves also a purpose to be hereinafter made clear.

The chamber member 31 is preferably of glass and is replaceable by reason of the hinged fastening of the canopy 16 to the ring member 15. Thus, when the canopy 16 is swung open, the chamber member 31 may be lifted out through the ring member 15, whose diameter is greater than the exterior diameter of the chamber 31 at its maximum cross-section.

In the operation of this apparatus the container 26 is provided with a liquid fuel preferably of the nature of alcohol and the combustion thereof is started at the wick 28. The air necessary to maintain this combustion is admitted through the perforations or apertures 30 and the products of combustion pass in an upward direction and eventually through the exit openings 38 in the

canopy 16. The rate of combustion is manually adjusted or regulated by determining the height or exposure of the wick 28 by means of the handle 29. The container 33 is sufficiently elongated so that it will extend to within a short distance of the wick itself and will therefore be in direct contact with the flame of combustion. In this manner the greatest intensity of heat, which is found in the flame of combustion, is applied directly to preferably a small portion of the receptacle 33, thus insuring that the melting of the contents may proceed with the greatest rapidity and effectiveness.

The chamber 31 substantially surrounding or inclosing the elongated receptacle 33 forms therebetween an annular path for the hot gases of combustion and such products of combustion pass in an upward direction in this annular path and contact with the lateral surface of the container 33 to maintain the contents in the melted or fluid state.

The annular path for the products of combustion provided for by the chamber 31 and the form of the receptacle 33 permits the hot gases resulting from the combustion to assist in melting the contents of the receptacle, the melting being started at the lower portion of the receptacle, where it is in direct contact with the heat of greatest intensity at the flame itself. The contents of the receptacle having been melted into a fluid state it is necessary only to maintain this fluid condition within the container and therefore it is necessary to transfer to the receptacle and its contents only a sufficient amount of heat to compensate for the heat losses by radiation, convection, or in other ways. It will be obvious, therefore, that this latter amount of heat is but small and by means of the apparatus of this invention this small amount of heat is produced simply by turning down the wick 28 to produce a smaller amount of gases of combustion and to allow such reduced amount of products of combustion to circulate upwardly through the annular space whereby the transfer of heat necessary to compensate for the above mentioned losses and to maintain a liquid state are most efficiently and effectively transferred to the receptacle and its contents. Thus there results a minimum consumption of fuel.

The contents having been liquefied may be poured from the container either by lifting the container itself from the heater by means of the bail 36 and using the container individually, or the entire apparatus may be tilted to pour the contents from the container by means of the spout 35. It will be noted that such tilting may be accomplished without interfering with the heating action or without interfering with the operation of the source of heat itself, and that the liquid state may be maintained by conserv-

ing the heat within the annular chamber as hereinbefore described, in spite of the change of position of the entire apparatus from normal. When the apparatus is tilted 5 as a whole to effect pouring of the contents from the receptacle 33, the chamber 31 and its associated parts are tilted about an axis passing substantially through the points at which the bail 22 is secured to the main 10 frame members. By reason of the length of the receptacle 33 its effective center of gravity is low, and particularly so because of its contents. During the conjoint tilting of both chamber 31 and receptacle 33, a relative swinging between these two parts takes 15 place, the low center of mass of the latter being effective to cause such action. There results, therefore a movement of the spout 35 away from the annular supporting member 32 so that the former clears the latter to permit proper and uninterfered function of the spout.

It will thus be seen that there is provided in this invention an exceedingly simple and durable melting apparatus of great effectiveness and efficiency of operation, such desirable operation not being disturbed by the actual use of the apparatus in pouring or by violent air currents, such as blasts of 30 wind, to which this apparatus is peculiarly susceptible in its adaptation to the operation of grafting during which it will be obvious that it must be used out of doors. It will be further noted that the several advantages heretofore pointed out, together 35 with others, have been attained and that the several objects of this invention have been effectively achieved.

As various possible embodiments might be 40 made of the above invention, and as various changes might be made in the embodiment above set forth, it is to be understood that all matter herein set forth or shown in the accompanying drawings is to be interpreted 45 as illustrative and not in a limiting sense.

I claim:

In apparatus of the class described, in combination, a substantially cylindrical chamber for conducting a heating medium, means secured to and positioned at the lower portion of said chamber for producing said heating medium, a bail secured to said chamber at two substantially diametrically opposite points whereby said chamber may be tilted substantially about an axis passing 50 through said points, a substantially cylindrical receptacle of lesser diameter than said chamber and of a length slightly less than that of said chamber provided with an outwardly extending lip and with a spout 55 formed at its upper edge portion, a substantially annular member secured at the upper part of said chamber having an opening of slightly greater diameter than the diameter of said receptacle for loosely receiving said 60 receptacle and supporting said receptacle entirely within said chamber by engagement with said lip, said annular supporting member being provided with a recess for accommodating said spout at a point in a 70 vertical plane substantially at right angles to the vertical plane passing through said two diametrically opposite points, whereby the upper edge of said receptacle and said spout is substantially flush with said annular supporting member and whereby, as 75 said chamber is tilted about an axis through said two points and in the direction of said recess, said receptacle is permitted to swing in its annular supporting member and with 80 in and relative to said chamber in the direction of the tilting of said chamber to swing said spout away from, and out of flush relation with, said annular supporting member to permit pouring of the contents from 85 said receptacle.

In testimony whereof, I have signed my name to this specification this 11th day of November 1919.

ROBERT T. MORRIS.
